UNITED STATES PATENT OFFICE.

FERDINAND JOHN, OF ERKELENZ, RHINELAND, GERMANY.

ROTARY-KEY COUPLING.

1,371,787.

Specification of Letters Patent. Patented Mar. 15, 1921.

Application filed September 18, 1920. Serial No. 411,273.

To all whom it may concern:

Be it known that I, FERDINAND JOHN, citizen of the German Republic, and resident of 50 Hindenburgstrasse, Erkelenz, 5 Rhineland, in the German Republic, have invented certain new and useful Improvements in Rotary-Key Couplings, of which the following is a specification.

In the usual rotary key couplings the rotary segmental key rests in inoperative position in a more or less half round groove or keyway in the shaft which is driven by a surrounding bush or the boss of a flywheel or gear wheel or the like. A stop carried 10 by the key abuts against a stop lever, which may be actuated by a pedal or the like. When so actuated, the key rotates under the action of a spring until it engages the complementary groove or keyway in the driving 15 bush. In order to obviate advance of the driven shaft in relation to the driving element when the coupling is thrown into gear, the bush carries a spring-controlled detent which snaps into a recess in the shaft or in 20 a cap or bush on the end of the shaft as soon as the coupling is effected. To effect this 25 action, the key and detent are arranged in the required relative position.

The key and detent are, however, inaccessible 30 without dismantling the coupling which is both difficult and tedious and frequently very inconvenient.

According to the present invention, the key and detent are readily accessible and 35 can also be actuated from the exterior in such a manner that the coupling may be adapted to new purposes, more particularly to machines which may become jammed or interlocked owing to obstructions. The improved 40 coupling enables the interlocked parts in such case to be gradually loosened by impact. Moreover, the machine may be driven forwardly or reversed, which is of great utility for adjusting certain tools.

The invention comprises the interconnection 45 of the key and detent by a detent element which may consist of a spring-controlled pawl adapted to lock the main detent in uncoupled position. When the key 50 is moved into coupling position, the key operates the pawl so that the main detent is released. The key, pawl and main detent may be secured in various positions by lock-

ing pins in order to enable the parts of the coupling to be set according to different requirements. 55

The improved coupling is illustrated in one example on the drawings, whereon,

Figure 1 is a transverse sectional view and Fig. 2 a longitudinal sectional view. 60 Figs. 3, 4, 5 and 6 are views corresponding to Fig. 1 but showing the parts in different positions.

The driven shaft *a* which may be the driving shaft of a press, is driven by a bush *b* which is shown fitted in the boss *b*¹ of a belt-driven fly wheel and keyed thereto by the studs *b*² (Fig. 2). The key *c* is fitted in the usual manner in a groove in the shaft *a* so that by the rotation of its arm *c*¹ it may 70 engage in one of the keyways *c*² of the bush *b*. When the lever *d*¹ is rocked about its pivot *d*² by downward movement of the rod *d* by pedal mechanism or the like, the arm *c*¹ is free to rotate and the key *c* then engages 75 the keyways under the action of the spring *c*³, which is located in annular groove *c*⁴ and has its end secured to pin *c*⁵ disposed transversely in this groove.

The detent *e* is mounted in a cap *f* fitted 80 on the end of the shaft *a* and connected with it by keys *f*¹. The detent is adapted to engage one of the recesses *e*¹ in the boss *b*¹ or in a ratchet ring secured thereto, under the action of a spring *e*². The detent *e* projects 85 through a cover *g* (Fig. 2) and is squared at *e*³ to receive a crank. The key *c* also projects through the cover *g* and is squared at *c*⁴ to receive a cranking tool.

A pawl *h* is mounted in a space between 90 the cap *f* and cover *g* and constitutes the interconnection between the key and detent. It is in the form of a double-armed lever pivoted at *h*¹ and pressed against a flat *h*³ on the key *c* by a spring *h*². In the coupled 95 position shown in Fig. 1, the pawl *h* locks with a nose *h*⁴ on the detent *e* so that the latter is held in uncoupled position.

The pintle *h*¹ of the pawl *h* is also squared 100 at *h*⁴ outside the cover *g*.

When the coupling is thrown into gear by depressing the lever *d*¹, the rotation of the key *c* causes the flat *h*³ to rock the pawl *h* and thus free the detent *e* which in turn immediately engages one of the recesses *e*¹ 105 of the boss *b*¹ under the action of the spring

e². The shaft and driving element are thus simultaneously coupled and locked in either direction, as illustrated in Fig. 3.

The uncoupling is effected in the usual manner on the upward movement of the lever *d¹* by the contact of the arm *c¹* therewith rotating the key *c* and withdrawing it from the key way in the bush into the position shown in Fig. 1, the pawl *h* returning 10 from the position shown in Fig. 3 to that shown in Fig. 1 under the action of its spring *h²*. The continued rotation of the bush *b* then presses the detent *e* into the uncoupled position, where it is held by the 15 pawl *h*.

It is of advantage to be able to hold the detent *e* in its uncoupled position. In the usual couplings in which the detent is not so held, the detent snaps into all the recesses 20 of the rotating bush, causing noisy running and considerable wear.

A great advantage of the improved arrangement is that the key and detent can both be moved into operative position independently, while one of them is inoperative and locked. The locking may be readily effected by hand manipulated locking pins.

Fig. 4 shows one position of the parts in 30 which the key *c* is locked in uncoupled position by a pin *i*. In such case the coupling cannot be thrown into gear by accidentally depressing the rod *d* or otherwise and work can thus be carried out on the machine without 35 danger.

The possible position of the parts shown in Fig. 4 is the principal advantage of the arrangement for machines which may, for example, become locked or jammed by excessive 40 stresses, enabling them to be readily re-set. In such cases it is frequently not possible to simply reverse the drive, while forcible forward drive would damage the machine.

45 The belt may however be readily reversed or the electric motor power reversed so that the gearing of the machine runs counter to the detent *e* and as soon as a moderate speed has been attained the belt may be shifted on 50 to the idle pulley or shifted off the flywheel or the motor stopped. Thereupon the pawl *h* may be turned by a crank to release the detent *e*, causing it to engage the first recess *e¹*, whereby the cap *f* takes up the energy stored by the flywheel by impact and rotates the shaft *a* backwardly. If this 55 operation is not sufficient to completely free the machine, it may be repeated and if necessary the mechanism may be allowed to attain a greater speed before the detent *e* is 60 released.

Figs. 5 and 6 show the coupling in positions required for the purpose of setting the machine tools. In Fig. 5 the key *c* and the

pawl *h* are locked by means of pins *i* and *k* 65 so that they are inoperative. Consequently the detent *e* is alone capable of movement so that on reverse movement, it must engage one of the recesses *e¹* as shown on the drawing. The reverse movement can then be 70 effected either by hand or by motor drive according to the size of the machine. In any case it is possible to transmit a certain impact through the detent *e* by adjusting the parts previous to reverse movement so 75 that a more or less partial rotation of the driving bush *b* must take place before the detent *e* snaps into place.

In the position shown in Fig. 6 both the pawl *h* and detent *e* are locked by means of 80 the pin *k* while the key *c* is free to rotate. This position of the parts may be employed when the setting of the tools requires a slow forward drive of the machine. In this position of the parts also a gradual step-by-step 85 forward drive of the machine may be obtained similar to the reverse drive above described by means of the detent *e*.

It is of course understood that the operative parts may vary from the construction 90 shown on the drawing and that the detent may also be constructed in the form of a rotary key in which case it would operate in the manner described if suitably connected with the key *c* by detent mechanism and 95 by other locking mechanism such as pins so that it may be locked in the various positions.

The examination, repair and interchange of the various parts of the coupling can be 100 effected without difficulty after the cover *g* is removed. This cover may be secured to the cap of the shaft by means of a few screwed studs.

If the coupling rotates at 120 revolutions 105 per minute, the detent *e* in the device hitherto known had to snap 240 times per minute into the recesses, as two recesses *e¹* were provided, thus causing the well known unpleasant whirring noise. It had, however, the 110 further disadvantage that this constant vibration caused premature wear and loosening of the parts. This is entirely excluded by the improved coupling because the pawl *e* is carried by the stationary cap when the 115 coupling is out of gear, being secured in the stationary position by the pawl *h* so that it must remain out of engagement with the recesses *e¹*. Consequently permanent stress on the detent spring *e²* is obviated so that 120 it is capable of correspondingly greater life. The same applies also to the other movable parts of the device.

Claims:

1. The combination with a shaft member, 125 of a hub member revolubly mounted on the same, a clutch element adapted to connect said shaft and hub whereby one of said

- members may be driven by the other, a detent carried by one of said members and adapted to engage the other member to prevent forward movement of the driven member relatively to the driving member, and a pivoted element operatively connecting the clutch element and detent whereby the detent may be operated simultaneously with the clutch element.
5. The combination with a shaft member, of a hub member revolvably mounted on the same, a rotary key clutch adapted to connect said shaft and hub whereby one of said members may be driven by the other, 15 said key having a cam surface, a detent carried by one of said members and adapted to engage the other member to prevent forward movement of the driven member relatively to the driving member, and a pivoted element having a portion resting against the cam surface of the rotary key and adapted to engage the detent when the key is rotated to inoperative position, to hold said detent in inoperative position.
20. 2. The combination with a shaft member, of a hub member revolvably mounted on the same, a rotary key clutch adapted to connect said shaft and hub whereby one of said members may be driven by the other, 25 said key having a cam surface, a detent carried by one of said members and adapted to engage the other member to prevent forward movement of the driven member relatively to the driving member, and a pivoted element having a portion resting against the cam surface of the rotary key and adapted to engage the detent when the key is rotated to inoperative position, to hold said detent in inoperative position.
25. 3. The combination with a shaft member, of a hub member revolvably mounted thereon, a clutch element adapted to connect said shaft and hub whereby one of said members may be driven by the other, a detent carried by one of said members and adapted to engage the other member to prevent forward movement of the driven member relatively to the driving member, a spring for normally forcing said detent into operative position, and a pawl arranged to be operated by the clutch element for holding said detent in inoperative position.
4. The combination with a shaft member, of a hub member revolvably mounted on the same, a clutch element adapted to connect said shaft and hub whereby one of said members may be driven by the other, a detent carried by one of said members and adapted to engage the other member to prevent forward movement of the driven member relatively to the driving member and a pivoted element operatively connecting the clutch element and detent whereby the detent may be operated simultaneously with the clutch element, said pivoted element being operable independently of the clutch element when desired.
5. A coupling comprising a driven shaft, a driving member embracing said shaft, a rotary key interposed in keyways between said driving member and driven shaft, a cap mounted on the end of said driven shaft, a detent mounted on said cap and adapted to engage recesses on the driving member, an interconnection between said detent and rotary key, and a removable cover for said cap having journals for said detent, pawl and key and means for operating said detent, pawl and key from outside the cover.

FERDINAND JOHN.
